UNITED STATES PATENT OFFICE.

WILLIAM S. RICHARDSON, OF BOSTON, MASSACHUSETTS.

DESIGN FOR A SOCKET MEMBER FOR SEPARABLE FASTENERS.

SPECIFICATION forming part of Design No. 27,537, dated August 17, 1897.

Application filed June 23, 1897. Serial No. 641,999. Term of patent 14 years.

To all whom it may concern:

Be it known that I, WILLIAM S. RICHARDSON, a citizen of the United States, residing at Boston, in the county of Suffolk and State of Massachusetts, have invented and produced a new and original Design for the Socket Member of a Separable Fastener, of which the following is a specification, reference being had to the accompanying drawings forming a part thereof.

In the drawings, Figure 1 is a view of the socket member in perspective. Fig. 2 is a view of the same in perspective inverted. Fig. 3 is a sectional view thereof.

15 The design comprises a flange a , preferably

circular in shape and preferably, but not necessarily, provided with holes, a wall a' , extending therefrom and at a right angle thereto, a flat section a^2 , an inner wall a^3 , extending from the flat section a^2 , and a narrow rim a^4 20 about the opening a^5 .

Having described my invention, what I claim as new, and desire to secure by Letters Patent of the United States, is—

The design for a socket member of a separable fastener herein shown and described.

WILLIAM S. RICHARDSON.
